United States Patent Office.

DANIEL J. TITTLE, OF ALBANY, NEW YORK, ASSIGNOR TO ABBIE M. TITTLE.

Letters Patent No. 66,418, dated July 2, 1867.

IMPROVED CAR-COUPINGS.

The Schedule referred to in these Letters Patent and making part of the same.

TO ALL WHOM IT MAY CONCERN:

Be it known that I, DANIEL J. TITTLE, of the city and county of Albany, State of New York, have invented certain new and useful Improvements in Car-Couplings, and the mode of operating them; and I do hereby declare that the following is a full, clear, and exact description thereof, of its construction and operation, reference being had to the annexed drawings, making a part of this specification; in which—

Figure 1 is a perspective view inverted.

Figure 2 is a view of draught-head secured.

Figure 3 is a cross-section view from beneath.

The same letters indicate like parts.

The nature of my invention consists of constructing the draught-bar with a hinge, placed at any suitable point between the draw-beam and the head of the said draught-bar, whereby the head is rendered free to move in a lateral direction, while the end of the bar will be held rigid in the draw-beam. To ease the coupling-heads, when being detached, I place a lever against the back end of the draught-bar and connect with its long end a rod or chain, or both, which is properly attached to the rack-wheel or segment-shaft, which shaft, when operated to throw the coupling-heads aside, will also draw the lever against the end of the draught-bar, and force it forward and thereby ease the uncouplings. To enable a person to uncouple the cars from the ground, I provide a lever on the under side of one of the outer beams of the car, one end of which has a rack, which operates in a second rack provided on the end of the rack-bar, which, when pulled out, throws the coupling-head to one side and at the same time operates the easing lever. To adapt cars of varying heights provided with the ordinary links for coupling with the coupling of my invention, I provide two or more slots horizontally cut in the ends of the double hook-heads, in either of which the links may be inserted; and to secure the heads together firmly I make in the heads an oblong hole, which runs down perpendicular through the whole depth of the head, and into one of these perpendicular holes I drop one leg of binding clevis, which is made U-shaped, while the other leg drops down back of the coupling-head or in the perpendicular hole of the co-acting coupling-head. By these improvements cars can be as readily uncoupled by a person standing on the ground on the side of a car as when on the platform, and when coupled can be secured from being disconnected while turning a curve, as has been proved by actual test; and cars with ordinary coupling-links with varying heights can also be accommodated.

In the drawings, A, figs. 1 and 3, represents the under side of a platform or a car, to which the coupling is attached. The draught-bar α is made in two pieces and provided with a hinge, c , placed at any suitable point between the draw-beam b and the double hook-head d , which permits the head to move in a lateral direction. Back of the draw-beam b , and against the end of the draught-bar α , is placed a lever, e , the short end of which is held by a suitable fulcrum, f . This lever e has provided on its longest end a suitable eye, or its equivalent, to which is connected a rod or chain, g , or both, which rod or chain is attached to the rack-wheel or segment-shaft s , which rack-wheel shaft, when turned in either direction, throws the double hook-head d to one side, and at the same time draws, by the rod g , the lever e against the end of the draught-bar α and throws it forward, so that by both the side and forward movements of the double hook-heads (shown by the dotted lines d' , fig. 3) the cars can be uncoupled with ease. To uncouple cars without the aid of the hand-wheel, I provide on one of the side beams A of the car a suitable lever, h , which turns on a proper pivot. The short end of this lever terminates in a rack, h' , which works another rack, i , on the end of shifting-bar k ; and when the long end of the lever is pulled out or pressed in the end rack h' operates the shifting-bar k and throws the double head d to one side, and at the same time operates the easing lever e and throws the head forward the same as if the operation were performed by the rack-wheel shaft s . To adapt my invention to the ordinary links used in coupling, and to the varying heights of cars, I make in the face of the double hook-heads d two or more horizontal slots $m m$. Into any of these slots the ordinary coupling-links can be inserted and secured by a suitable pin, as in the ordinary way; and to prevent the cars from uncoupling when on a curve, &c., (as experiment has shown they will do when not secured,) I make a perpendicular hole, n , through the whole depth of the head d , through which I insert one leg of the U-shaped clevis O , figs. 2 and 3, and drop the other leg down back of the head d ,

or in a similar hole, n' , of a co-acting head. Both legs of said clevis are made of sufficient length to preclude all possibility of its jumping out by any jolting.

What I claim as my invention, and desire to secure by Letters Patent, is—

1. I claim the lever e , fulcrum f , and the rod or chain g , or both, in combination with the rack-wheel shaft s , as and for the purpose described.
2. I claim the lever h , with the rack h' and the rack i , in combination with the shifting-bar k , for the purpose set forth and described.
3. I claim the hinged draught-bar α α , in combination with the lever e , fulcrum f , rod and chain g , or both, operated by the lever h or rack-wheel shaft s , as and for the purposes described.
4. I claim the hook-head coupling perforated as described, in combination with the clevis O , or its equivalent, as and for the purposes set forth and described.

DANIEL J. TITTLE.
